STEEL SPACE HEATER CONSTRUCTION

Homer D. Du Fault, Easthampton, Mass., assignor to
Heathbath Manufacturing Company, Inc., Indian
Orchard, Mass., a corporation of Massachusetts
Filed July 15, 1960, Ser. No. 43,212
2 Claims. (Cl. 126—90)

The present invention relates to improvements in space heaters of the type which are installed in a semi-permanent fashion to heat a single room or a relatively localized area.

The object of the invention is to reduce the cost and simplify the maintenance of such space heaters and at the same time increase the efficiency with which the fuel is used in heating the area in which the space heater is installed.

The above and other related objects, as well as the constructional features of the invention, will be apparent from a reading of the following description of the disclosure found in the accompanying drawings and the novelty thereof pointed out in the appended claims.

In the drawings:

FIG. 1 is a front elevation, with portions broken away and in section, of a space heater embodying the present invention;

FIG. 2 is an end elevation of the space heater;

FIG. 3 is an exploded end elevation with portions cut away and in section; and

FIG. 4 is a plan view of the space heater with its cabinet removed and portions thereof broken away and in section.

With reference to the drawings, and particularly FIG. 3 thereof, the present space heater comprises three basic sheet metal members which are pre-assembled as units capable of easy assembly and disassembly. The three sheet metal units comprise a cabinet 10, a firebox 12 and a frame 14.

The cabinet 10 comprises a rectangular welded sheet metal frame having inturned flanges 16 (FIGS. 1 and 3) defining an opening in the front panel thereof. Sides 18 of the cabinet are illustrated as solid sheet metal walls or panels, while an opening 20 in the top panel of the cabinet is closed off by a sheet 22 (FIG. 4) of perforated metal. Inturned flanges 24 define the rear edges of the side panels 18, while inturned flanges 26 define the lower edges of the said side panels 18. A U-shaped sheet metal channel 28 (FIG. 1) extends between the upper and lower flanges 16. A cross channel member 30 extends between the left hand flange 16 and the vertical channel 28. A sheet of perforated metal 32 fills the opening between left hand flange 16 and the channel 28. The sheet metal 32 is secured to the front portion of the top flange 16, trained behind the channel 30 and then secured to the front portion of the lower flange 16 for decorative purposes. It will also be noted that a louvered door 34 fills the opening between the channel 28 and the right hand flange 16 being pivoted at 35 relative to the upper and lower flanges 16.

The firebox 12 (FIG. 3) is a welded sheet metal assembly open at its lower front end to receive the combustion products of an open flame burner 36. Internal baffles 38 and 40 create a reverse path of flow of the heated gases and a maximum transfer of heat to the outer walls of the firebox. The heated gases will pass through a flanged discharge opening in the form of an outlet pipe 42 to a flue box, later described.

The frame 14 comprises a base plate 44 which is folded upwardly at its rear edge to form a back plate 46. An angle plate or gusset 48 (see also FIG. 4) is welded along the right hand marginal edge portions of the base plate 44 and back plate 46. A side plate 50 is also welded to

2

the bottom plate 44 and back plate 46 adjacent the opposite ends thereof. An intermediate vertical divider plate 52 is welded to the back plate 46 and a tie plate 54 extends between and is welded to inturned flanges of the side plate 50 and divider plate 52. The divider plate 52 separates the frame member into a heater area which receives the firebox 12 and burner 36 and a controls area in which a control unit is mounted, as will later appear.

Channel members 56 run parallel to and adjacent the front and rear edges of the bottom plate 44. A pair of legs 58 underlie the channels 56 and are secured thereto to support the frame 14 as well as the firebox 12 and cabinet 10 when the latter two units are mounted in place. An angle member 60 is secured to the front face of the front channel 56. The angle 60 is spaced above the base plate 44 a distance somewhat greater than the thickness of an inturned lip 62 (FIG. 3) running along the bottom edge of the cabinet 10 for purposes which later appear. An opening 64 is formed in the back plate 46 to more or less snugly receive the outlet pipe 42 on the firebox 12. On the rear of the back plate 46 is secured a flue box 66 into which the hole 64 opens. The flue box 66 is open at its lower end and is provided with a circular rim 68 defining an opening in its upper wall for attachment to a flue pipe (not shown).

In assembling the above-described units, the firebox 12 is mounted on a pair of posts 70 which project upwardly from and are secured to the front channel 56 (see also FIG. 2). The front wall of the firebox 12 is outwardly flanged and apertured to receive the reduced upper ends of the post 70. Nuts 72 rigidly secure the front portion of the firebox 12 relative to the frame 14. The outlet pipe 42 of the firebox is projected through the hole 64 and rests on the lower edge thereof. It will be seen that the firebox is supported in part by the base plate 44 and in part by the back plate 46. An angle strap 74 is welded to the back panel 46 above the hole 64 and apertured to receive a sheet metal screw 75 which will pass therethrough and thread into the outlet pipe 42 thereby positively locating the firebox 12 in a fore and aft sense relative to the frame 14.

There are few repairs which will require removal of the firebox 12 from the frame 14. However, if the need should ever occur, it is a simple and easy matter. Of greater importance is the ease of mounting the firebox in its original assembly. This facility adds to the savings that are possible in the cost of manufacturing the present space heater.

The burner 36 is preferably, but not necessarily, of the open flame type being disposed in the bottom opening (seen in FIG. 3) running along the lower front portion of the firebox 12. The burner 36 is held in place by brackets 79 secured to the end walls of the firebox 12. Secured to the divider plate 52 is a sheet metal bracket 80 (FIG. 4) on which is mounted a thermostatic control unit 82. A pipe 84 (FIG. 2) connects the control unit 82 with a supply line for natural or artificial gas. A tube 86 leads from the control unit 82 to the burner 36 and a tube 88 also leads therefrom to a pilot light in the burner 36. It will be noted that the control knobs for the control unit 82 lie behind the door 34 and are readily accessible for adjustment simply by opening the door 34.

The cabinet 10 is readily mounted on the frame 14 by sliding the flanges 26 (see FIG. 4) thereof over and along the marginal side edge portions of the base plate 44. As this is done, just slightly before the flanges 24 engage the back plate 46, the lip 62 (at the lower front edge of the cabinet) will be caught beneath the angle member 60 thereby anchoring the front portion of the cabinet relative to the frame. Four sheet metal screws 76 pass through openings provided in the back plate 46 and are threaded into the flanges 24 thereby effectively anchoring

the rear portion of the cabinet 10 relative to the frame 14.

The simplicity and ease of assembly is apparent from the fact that the cabinet can be mounted or disassembled simply by inserting or removing the four screws 76. This, of course, reduces the costs of original manufacture and simplifies later repairs. Minor repairs and adjustments can be readily made by opening the door 34 to gain access to the controls area of the space heater.

It will, of course, be appreciated that the thickness of the various sheet metal parts has been exaggerated to some extent in the drawings for the sake of clarity. It has been found that for most items a relatively light gauge metal can be used so that the overall cost of the present space heater is considerably reduced when compared with space heaters of conventional construction. In this regard particular note is taken of the firebox 12 and the manner in which it is mounted.

Having thus described the invention, what is claimed as novel and desired to be secured by Letters Patent of the United States is:

1. A space heater comprising a unitary frame member having rectangular base and back plates, the back plate having an opening adjacent the upper end thereof and a flue box supported on the rear face of the back plate communicating with said opening, an internally baffled sheet metal fire box having a front wall defining in part a bottom opening therefor and an outlet pipe at the upper rear portion thereof, said base plate having upstanding legs adjacent the front thereof, the said outlet pipe of the fire box extending into said back plate opening and detachably secured therein for supporting the rear of the fire box, and the said legs of the base detachably secured to the said front wall of the fire box for supporting the box at the front thereof in an elevated position above the base, and a cabinet having top, front, and side panels with the side panels thereof being slidably supported on said base plate, and fastening means detachably securing the cabinet side panels to the said back plate. 30

2. A space heater comprising a unitary frame member having sheet metal rectangular base and back plate portions bent at right angles to each other, the back plate portion having an opening adjacent the upper end thereof and a fluebox supported on the rear face of the back 40

5

plate communicating with said opening, a sheet metal vertical divider plate portion secured to said back plate and extending forwardly therefrom to separate the frame member into a heater area and a controls area, the latter being of lesser widthwise extent, an internally baffled sheet metal fire box disposed in said heater area and having a front wall defining in part a bottom opening therefor and an outlet pipe at the upper rear portion thereof, said base plate having a reinforcing channel member with upstanding legs fastened thereto adjacent the front thereof in said heater area, the said outlet pipe of the fire box extending into said back plate opening and detachably secured therein for supporting the rear of the fire box, and the said legs of the base detachably secured to the said front wall of the fire box for supporting the box at the front thereof in an elevated position above the base, said fire box having mounted therein a fuel burner unit in said bottom opening, a controls unit mounted on said divider plate and connected with and controlling flow of fuel to said burner unit, means bracing said base, back and divider plate portions including an end wall defining with said divider plate the said heater area of the frame, a cabinet having top, front and side panels with the side panels thereof being slidably supported on said base plate, fastening means detachably securing the cabinet side panels to the said back plate, the front and top cabinet panel portions coextensive with said heater area of the frame being of open work construction and said front panel having access door mounted in front of said controls area.
